UNITED STATES PATENT OFFICE.

SPENCER OTIS, OF CHICAGO, ILLINOIS, ASSIGNOR TO NATIONAL BOILER WASHING COMPANY, OF CHICAGO, ILLINOIS, A CORPORATION OF MAINE.

APPARATUS FOR WASHING OUT AND REFILLING BOILERS.

1,418,092.

Specification of Letters Patent. Patented May 30, 1922.

Application filed May 15, 1919. Serial No. 297,220.

To all whom it may concern:

Be it known that I, SPENCER OTIS, a citizen of the United States, residing at Chicago, in the county of Cook and State 5 of Illinois, have invented certain new and useful Improvements in Apparatus for Washing Out and Refilling Boilers, of which the following is a specification.

My invention relates in general to apparatus for washing out and refilling boilers, and more particularly to simplifying, and at the same time increasing the efficiency, of such apparatus.

The primary object of my invention is 15 to provide a boiler wash-out and refilling apparatus in which a single tank serves to directly receive the blown-off water and steam from the boiler, and to contain the supply of wash-out water, and in which the 20 steam is separated from the blown-off water and the sludge separated from the wash-out water, thereby obviating the need of the usual separator in which the blown-off fluids are received and by which the steam and 25 sludge are eliminated before the water is delivered to the wash-out tank.

A further object of my invention is to provide in a locomotive boiler wash-out apparatus a tank for receiving the blown-off 30 fluid directly from the boiler and from which is automatically discharged the sludge when the water level in the tank is at a predetermined height.

A still further object of my invention is 35 to provide in a locomotive boiler wash-out and refilling apparatus, a tank for receiving the blown-off fluids having a valve through which the sludge is discharged, which valve is automatically opened when 40 the level in the tank reaches a predetermined maximum and is retained open until the level falls a predetermined amount.

The final object of my invention is to 45 provide a boiler wash-out and refilling system which will be simple in construction, economical in use, and efficient in operation.

My invention will be more fully disclosed hereinafter with reference to the accompanying drawing, in which the same is 50 illustrated as embodied in a convenient and practical form and in which—

Figure 1 is a plan view, parts being shown in section; and,

55 Figure 2 is an elevational view, the tank

for the wash-out water being shown in vertical section.

The same reference characters are used to designate the same parts in the two figures of the drawing.

A designates a tank of a size and shape suitable for containing water for washing out locomotive boilers. The tank preferably comprises a cylindrical wall and horizontal top and bottom head B and C, respectively, 60 the parts being so connected as to render the tank substantially fluid-tight. The upper head of the tank is suitably supported, as by means of uprights D, upon the upper ends of which are supported horizontal bars D¹ which underlie and support the top head of the tank.

E indicates a conduit communicating with the interior of the tank A, preferably by extending through an opening located centrally in the upper head B, such conduit being connected in the usual manner with locomotive boilers which are to be blown off. Suitably supported within the tank A adjacent the under surface of the upper head 70 B, is a deflector F, preferably slightly conical and having a central hole f. A supplemental deflector F¹ is supported upon the deflector F over the hole f therethrough. The deflectors are located beneath the discharge end of the conduit E and preferably 75 concentric with respect thereto and also preferably concentric with respect to the tank.

G indicates a float which supports, in 80 any suitable manner, an open conduit H through which wash-out water is supplied from the tank to the usual wash-out conduit K. The float serves to support the open end of the conduit H adjacent the level 95 of the water in the tank so as to avoid the delivery of sludge, which settles at the bottom of the tank.

L designates a drain conduit leading from an opening in the bottom head C of the 100 tank, and which communicates with a conduit L¹ leading to the sewer. The conduit L¹ extends upwardly and communicates through a branch conduit l¹ with the interior of the tank adjacent the top thereof so as 105 to serve as an overflow.

M indicates a float chamber suitably supported adjacent the tank A, as by means of a tubular standard M¹ mounted at its lower end upon a T coupling l and the conduit 110

L. A float N is located within the chamber M and is connected by a rod N¹ with a valve n located in the T coupling l and serving to open and close the passageway 5 through the conduit L. A conduit O leads from the interior of the tank A adjacent the top thereof to the interior of the chamber M, such conduit being in the form of a siphon, one leg of which depends a limited 10 distance within the tank A and the other leg of which depends to adjacent the bottom of the chamber M, where it is preferably provided with a gravity valve o. P designates a drain pipe of restricted cross 15 section with respect to the cross section of the conduit O, which may preferably communicate at its lower end with the drain pipe L¹.

R designates a conduit communicating 20 through the upper head B with the interior of the tank A and leading to a condenser S, into which cold water received through a conduit S¹ is sprayed. s indicates a support for the condenser, and s¹ a conduit leading 25 from the condenser for delivering water of condensation into the tank T for containing water for refilling the boilers.

The operation of my invention is as follows: The fluids blown off from the boilers 30 are delivered through the conduit E to the interior of the tank A immediately above the deflectors F and F¹ so that the water is directed toward the side wall of the tank. Steam which rises from the water below the 35 deflector F passes through the hole f therein, and together with the steam directly delivered through the conduit E passes through the conduit F to the condenser S, where it is condensed and then passes in the form of 40 water condensation into the refilling tank T.

The float G supports the eduction conduit H centrally beneath the deflector F so that the wash-out water withdrawn from the tank 45 is free from sludge which settles adjacent the cylindrical wall of the tank owing to the deflector F.

When the level of the water in the tank A rises above the horizontal portion of the 50 conduit O, it flows through such conduit into the chamber M and lifts the float N, thereby opening the valve n and permitting the sludge to be discharged from the tank to the sewer conduit L¹. The water will continue 55 to flow to the chamber M and maintain the valve n open until the water level in the tank A falls below the lower end of the leg of the siphon depending within the tank, the siphon being then broken the float will lower and permit the valve n to close owing 60 to the discharge of water from the chamber M through the restricted drain P. The drain P is normally open but it is of sufficiently less capacity than that of the conduit O to not interfere with the accumulation of 65 water in the chamber M to operate the float

N. Leakage from the chamber around the rod N¹ is prevented by means of suitable packing n¹ in the opening in the bottom of the chamber through which the rod extends.

The presence of the baffles effects the distribution of the sediment and sludge adjacent the sides of the cylindrical wall on the bottom of the tank so that as the eduction port is supported adjacent the center of the tank the water for washing out boilers is 70 supplied free from sludge. The provision of the hole through the deflector permits the upward passage of steam rising from the water, while the small deflector supported above the hole in the larger deflector prevents the incoming blown-off fluids from 75 passing through the hole in the main deflector, while the steam is permitted to pass through the space between the two deflectors.

It will be evident that my invention comprises a combined blow-off, separator, and wash-out water tank, inasmuch as blown-off 80 fluids are discharged directly into the tank, and the steam and sludge eliminated from the blown-off water, so that the tank contains 85 water for use in washing out boilers.

From the foregoing description it will be observed that I have invented an improvement in apparatus for utilizing the fluids discharged from boilers in forming water 90 for washing out and refilling boilers, by means of which a single tank serves to receive the blown-off fluids and to effect the separation of the steam and sludge from the fluids so that water may be delivered 95 directly from the tank for washing out 100 boilers. It will be further observed that by means of my invention the sludge is automatically discharged from the tank when the water level therein reaches a predetermined 105 height and that such discharge will continue until the level has fallen a predetermined degree.

While I have in this application specifically described one embodiment which my 110 invention may assume in practice, it is my intention to cover all modifications of the invention which do not involve a departure from the spirit and scope of the invention as set forth in the following claims.

I claim:

1. A boiler blow off and wash-out system comprising a tank having a single compartment in which it receives and separates steam, water and sludge, means delivering 120 steam, water and sludge from locomotives, directly and collectively to said tank, means conveying away steam from the top of said tank, means conveying away sludge from the bottom of said tank, and means drawing off wash-out water from the upper portion of said tank below the water level therein.

2. In a boiler wash-out and refilling system, the combination with a tank for 130

receiving the blown-off fluids from a boiler, of means automatically controlled by the liquid level in said tank for permitting the discharge of sludge therefrom, and a conduit for supplying water from said tank for washing out boilers.

3. A boiler blow off and wash-out system comprising a tank having a single compartment in which it receives and separates steam, water and sludge, means delivering steam water and sludge from locomotives directly and collectively to said tank, means conveying away steam from the top of said tank, a sludge conduit for drawing off sludge from the bottom of said tank, means responsive to an excessive water level for automatically opening said sludge conduit, and a conduit for wash-out water leading from the upper portion of the tank below the normal water level thereof.

4. A boiler blow off and wash-out system comprising a tank having a single compartment in which it receives and separates steam, water and sludge, means delivering steam, water and sludge from locomotives directly and collectively to said tank, means conveying away steam from the top of said tank, a sludge conduit for drawing off sludge from the bottom of said tank, means responsive to an excessive water level for automatically opening said sludge conduit, and a conduit for wash-out water leading from the upper portion of the tank below the normal water level thereof; means being also provided to vary the level of the wash-out water conduit with changes in the water level within the tank.

5. In a boiler wash-out and refilling system, the combination with a tank and means for delivering to said tank, directly and collectively, steam, water and sludge blown off from a locomotive, of a deflector supported within said tank, a blow-off conduit communicating with the interior of said tank above said deflector, and a conduit extending from below said deflector through which wash-out water is withdrawn.

6. In a boiler wash-out and refilling system, the combination with a tank and means for delivering to said tank, directly and collectively, steam, water and sludge blown off from a locomotive, of a conical deflector supported within said tank and having a hole at its apex, a supplemental deflector supported above the hole in said conical deflector, a blow-off conduit above said deflectors, a conduit extending from below said deflectors through which wash-out water is withdrawn, and a steam discharge conduit leading from the top of said tank.

7. In a wash-out and refilling system, the combination with a tank, of a conduit through which fluid blown off from boilers is delivered into said tank, a valve for control-

ling an outlet from the bottom of said tank, and means for opening said valve when the water level of said tank reaches a predetermined height and for retaining said valve open until the water level falls a predetermined degree.

8. In a boiler wash-out and refilling system, the combination with a tank, of a conduit communicating with said tank for supplying thereto fluids blown off from boilers, a drain conduit leading from adjacent the bottom of said tank, a valve controlling the flow through said conduit, a float chamber, a float in said chamber operatively connected to said valve, a conduit through which water is supplied from said tank to said chamber during a predetermined high water level in said tank, and a relatively restricted discharge port adjacent the bottom of said chamber.

9. In a boiler wash-out and refilling system, the combination with a tank, of a conduit communicating with said tank for supplying thereto fluids blown off from boilers, a drain conduit leading from adjacent the bottom of said tank, a valve controlling the flow through said conduit, a float chamber supported adjacent said tank, a float in said chamber operatively connected to said valve, a siphon conduit, one leg of which depends in said tank and the other leg of which depends within said chamber, and means for discharging the water from said chamber when the flow through said siphon is broken.

10. In a boiler wash-out and refilling system, the combination with a tank, of a conduit communicating with said tank for supplying thereto fluids blown off from boilers, a drain conduit leading from adjacent the bottom of said tank, a valve controlling the flow through said conduit, a float chamber supported adjacent said tank, a float in said chamber operatively connected to said valve, a siphon conduit, one leg of which depends in said tank and the other leg of which depends within said chamber, and a normally open drain pipe leading from adjacent the bottom of said chamber of less cross section than the cross section of said siphon.

11. In a boiler wash-out and refilling system, the combination with a tank, of a deflector supported within said tank, a blow-off conduit communicating with the interior of said tank above said deflector, a conduit through which wash-out water is withdrawn from said tank, and means for supporting said latter conduit beneath said deflector at a predetermined distance below the water level.

12. In a boiler blow off refilling system, a combination single compartment tank having a pipe delivering directly thereto blown-off steam, water and sludge from a loco-

- motive; said tank being adapted to separate the steam and sludge from the water therein, and to draw off said steam from the top and said sludge from the bottom of the tank while storing the water, and having means for delivering water from the upper portion thereof below the water line therein.
13. In a boiler wash-out and refilling system, the combination with a combined blow-off, separating and wash-out water tank, of means for automatically discharging the sludge from said tank.
14. In a boiler wash-out and refilling system, the combination with a combined blow-off, separating and wash-out water tank, of a deflector supported within said tank below the incoming blown-off fluids, and an outlet conduit for wash-out water extending from below said deflector.
- 20 15. In a boiler wash-out and refilling system, the combination with a combined blow-off, separating and wash-out water tank, of a deflector supported within said tank below the incoming blown-off fluids,

an outlet conduit through which wash-out 25 water is delivered from said tank, and means for supporting said latter conduit beneath said deflector at a predetermined distance below the water level.

16. In a boiler wash-out and refilling 30 system, the combination with a combined blow-off, separating and wash-out water tank, of a deflector supported within said tank below the incoming blown-off fluids and having a hole therethrough for the upward passage of steam, a second deflector spaced apart from and supported over the hole in said first deflector, a conduit leading from adjacent the top of said tank through which steam is discharged, an outlet 35 conduit for wash-out water, and means for supporting said latter conduit beneath said deflector at a predetermined distance below the water level.

Signed at Chicago, Illinois, this 13th day 45 of May, 1919.

SPENCER OTIS.
